UNITED STATES PATENT OFFICE.

RALPH L. SKINNER, OF DETROIT, MICHIGAN, ASSIGNOR TO SKINNER AUTOMOTIVE DEVICE CO., INC., OF DETROIT, MICHIGAN, A CORPORATION OF MICHIGAN.

APPARATUS FOR PURIFYING LUBRICATING OIL.

Application filed August 9, 1924. Serial No. 731,236.

My invention relates to certain features of improvement and novelty in the construction and manner of functioning of separator traps or rectifiers, such as are used, for example, in association with internal-combustion engines or motors to reclaim or purify mixtures of gaseous and liquid fluids drawn off from the motor, and purified in such tank or rectifier, the reclaimed fuel and other gases and vapors flowing into the intake-manifold of the motor for consumption therin and the separated and purified lubricant being returned intermittently to the lubricating system of the motor.

This invention pertains more particularly to the means for heating the tank or a portion thereof to aid in the vaporization or gasification of some of the ingredients of the mixture and to the automatic control of the action of the heating means whereby to prevent an undue rise in temperature of the lubricant.

Another feature of the invention resides in the combination and cooperation of the automatic controlling means with the other instrumentalities of the appliance.

To enable those skilled in this art to have a full and complete understanding of the invention both from structural and functional standpoints, in the accompanying drawings, forming a part of this specification, a desirable and preferred embodiment of the invention has been illustrated in detail, and throughout the several views of these drawings like reference characters have been employed to designate the same parts.

In these drawings:

Figure 1 is a vertical, central section through the improved oil purifying apparatus;

Figure 2 is a horizontal cross-section on line 2—2 of Figure 1, the parts being viewed in the direction indicated by the arrows;

Figure 3 is a similar cross-section on line 3—3 of Figure 1, the parts being viewed in the direction indicated by the arrows;

Figure 4 is a fragmentary, vertical section on line 4—4 of Fig. 3 through the appliance and at right angles to the plane of section of Figure 1, the latter section being indicated by line 1—1 of this Figure 4;

Figure 5 is a fragmentary, vertical section on line 5—5 of Figure 3 showing the fluid inlet for the separating tank; and

Figure 6 is an enlarged, fragmentary, vertical section on line 6—6 of Figure 3.

Referring to these drawings, a round, division-wall casting 21 of suitable shape has fastened to it by means of screws 22, 22, a lower, cylindrical storage-compartment shell or casing 23, and, by means of screws 24, 24, an upper, cylindrical, vaporizing-chamber casing or shell 25, the two members 23 and 25 forming complementary parts or sections of the separating tank as a whole.

Upstanding from the downwardly-dished or concaved top surface 26 of the member 21 are two bosses 27 and 28 of the same height which support a cylindrical, sheet-metal cup 29 with its upright, round wall arranged concentrically with and spaced inwardly away from the side wall of the upper shell 25, the top edge of the part 29 terminating a distance below the top, slightly-domed, top wall of such shell, as is fully shown in Figure 1.

The flat, round, bottom wall of the cup or receptacle 29 is apertured in register with a threaded cavity in the top of boss 27 and a securing screw 31 fitted with a lock-washer 80 extends through such aperture and coacts with the threads of the recess to hold the cup fixedly in position.

Boss 28 has a partially-threaded passage 32 extended through it and the member 21, forming an air-discharge port from the lower storage compartment 37 into the upper separating chamber 36 inside of the cup-shaped receptacle 29 and a hollow, shouldered, threaded, stand-pipe exhaust-member 90 33 extends through a hole in the bottom wall of the cup and coacts with the internal threads of port 32 to assist in holding the parts in their correct assembled relation.

Boss or lug 28 is also provided with an oil-port 34 in register with a hole 35 in the bottom wall of the cup, whereby the contents of the latter may be discharged therethrough into the lower oil storage-compartment 37 formed by the shell 23 as has been 100 already explained.

It is to be observed that the top of the

stand-pipe 33 is some little distance above the bottom wall of the cup or receptacle 29 whereby the air and gases flowing upwardly therethrough will not interfere with the free 5 downward passage of the liquid lubricant through its adjacent oil-port 34.

The shell 25 of the upper, separating-chamber 36 is encased in a heater-shell 38 having an entrance 39 and a discharge 41 for 10 hot exhaust gases from the motor with which the appliance is used in order to give such separating-chamber adequate heat for distillation purposes.

The upwardly-arched top walls of the 15 two, nested, concentrically-arranged, cylindrical, shell members 25 and 38 are apertured to receive a headed, hollow bolt or connection 42 which by its bottom flange or small head supports a sheet-metal cup 43 20 inside of the companion cup 29 with its lower edge some distance above the bottom wall of the larger, enclosing cup, the two interfitting cups constituting barriers and forming a tortuous passage inside of the 25 heated separating-chamber.

A nut 44 on the externally-threaded part 30 of the fastener 42 holds the three elements 43, 25, and 38, together in the relation described and fully shown, and the member 42 connects with a pipe 45 communicating with the intake-manifold of the motor or with any other suitable means for producing a suction or sub-atmospheric pressure in the tank.

35 Such suction draws into the separating or distilling chamber 36 a fluid mixture of gases, air and lubricating oil through a suitable inlet port 46 in the division wall member 21 which, by means of appropriate piping, is directly connected to some portion of the lubricating system of the motor.

As is indicated in Figure 1, member 21 has a downwardly-opening air-inlet port 47 45 supplied with a lateral extension 48 opening through the side of part 21 to the outer atmosphere, such port 47 being normally closed by a downwardly-closing valve 49.

The division wall also has another port 51 therethrough controlled by an upwardly-closing valve 52 having a loose connection with or sliding connection through a hole in the end portion of a two-metal or duplex thermostatic bar 53 fastened at its other end by means of a screw 54 on the top of a ledge 55 constituting part of the division wall casting 21, the top end of the stem of valve 52 having a head 56 larger in diameter than the hole through the thermostatic bar and hence limiting the descent of the valve, the construction being such that, when the thermostatic element becomes heated by the oil after the latter is hot it flexes downwardly, thus permitting the valve to descend and open the port, yet if conditions are right, as 60 explained hereinafter, the valve may close 65

by reason of upward suction action thereon even though under heat the thermostatic bar is bent down which would otherwise cause the valve to be in open position.

To regulate the temperature at which the 70 thermostatically-controlled valve will open, a screw 57 is extended downwardly through a hole in the bar 53 and threaded into a screw-threaded cavity 58 in wall 21 and between the top face of the latter and the 75 under face of the thermostatic bar a spring 59 is interposed encircling the screw.

The turning of this adjustment screw puts more or less of an original or initial bend or flexure in the bar thus modifying the temperatures at which the valve will open and close. 80

A lever 61 fulcrumed at 62 on the underside of the division wall casting has an aperture accommodating the depending shank 85 or stem 63 of air-inlet valve 49 which is equipped with comparatively widely spaced shoulders 64 and 65 on opposite sides of the lever, whereby the movements of the latter will transmit hammer blows to the shoulders 90 either to open or close the valve.

Lever 61 also has a hole accommodating the double-shouldered stem 66 of an upwardly-closing air-escape valve 67 coacting with port 32 and in addition such lever has a hole receiving the single-shouldered shank 67^a of an upwardly-closing valve 68 cooperating with the oil-port 34, the construction being such that when the lever rocks upwardly it positively closes the two ports 32 100 and 34 by their valves and positively opens the air-inlet port 47, 48, by its valve 49, but when the lever swings down it positively opens the air-discharge port 32 and similarly closes air-inlet port 47, 48, but the port 34 105 may remain closed by its valve 68 so long as the pneumatic conditions in the tank require it.

Another oppositely-arranged lever 71 is also fulcrumed at 62 and laterally extended arms on the two levers are connected together by a pair of coil, contractile springs 72 adapted to pass by the fulcrum as the levers are rocked all as is well understood to secure a quick snap action of the valve operating parts. 110

Lever 71 is limited as to its rocking movements by means of opposed shoulders 73 and 74 on the casting 21 and which the extreme end of the lever overlaps. 115

A link 75 connects lever 71 to a rock-arm 76 hinged to the casting 21 at 77 such arm being pivotally connected at 78 to a float 79 in the storage-compartment 37 and encircled by a coil guide-spring 81. 120

The bottom of shell 23 and its compartment 37 is supplied with a pipe fitting having an upwardly-closing ball check-valve 82 and such fitting by a pipe, not shown, is connected to the oil supply system or other part 125 130

of the lubricating system of the motor, whereby when the ball-valve is open, the oil in the compartment is delivered back to the motor, the opening movement of the ball being limited by the supporting cross-pin 83.

When the motor and the separating chamber are cold, and the motor is first started, it is necessary that the liquids of the mixture of oil, gases, vapors and air, drawn off from the motor and delivered into the separating chamber should be retained therein a sufficient length of time until adequate heat is developed and imparted thereto to vaporize or volatilize their gasifiable or vaporizable constituents, but the structure should be automatically governed and controlled so that excess heat will not be imposed on such liquids when the parts have all become well heated under the running of the motor.

Accordingly, when the motor is first started the parts will be in the positions shown in the several views of the drawings, valves 52 and 49 being closed and valves 67 and 68 being open.

As the liquids are delivered into the separating chamber through the inlet 46 they accumulate therein and their top level gradually ascends in the annular heating space between the spaced cylindrical walls of the parts 29 and 25.

Of course the gases, vapors and air flow off through the pipe 45, their entrained liquids being expelled therefrom as they pass around the bends of the circuitous passage through the separating chamber, the walls of the parts 29 and 43 constituting barriers.

Thus we are assured that all oil which overflows into the cup 29 and then passes down through the open port 34 into the lower storage-compartment 37 has been subjected to adequate distilling heat because it has been compelled to flow slowly upwardly in contact with the inner wall of the surrounding hot exhaust-gas jacket.

This insures that all such oil has been freed from its vaporizable and gasifiable ingredients due to its simultaneous subjection to heat and sub-atmospheric pressure.

The oil accumulates in the manner specified in the space indicated because the cross-section of the latter is much larger than the caliber or area of the inlet-port 46 and the pipe associated therewith; or stated somewhat differently, the suction or sub-atmospheric pressure present is sufficient to carry along the contaminated lubricating oil with the gases through the pipe leading to the separating chamber, but in the latter, owing to its greater cross-section, it is insufficient to carry along the oil and this therefore accumulates in the way stated.

If, upon starting the cold motor, the oil were permitted to accumulate immediately

in the annular heating space between the two shells, the exhaust gases might not heat up the parts sufficiently rapidly to heat all liquids properly before some would overflow inwardly into the cup 29 and accordingly a substantial space is provided below the receptacle 29 and the heating shell 38 to accommodate the liquids drawn off from the motor until the exhaust gases have heated the jacket adequately, whereupon the liquids accumulate and fill up the heating space.

Thus we are reasonably sure that no improperly or inadequately heated oil can find its way into the cup and from thence into the lower storage-compartment.

As soon as correct heat conditions have been attained, and the motor and the separating chamber are properly heated, it will no longer be desirable to heat the oil in the chamber, as it will be at adequate temperature as withdrawn from the motor, and the thermostatic bar, which is itself immersed in the oil in the tank, bends downwardly due to the heat of the oil and permits valve 52 to open under its own weight and that of the oil above it, but it is to be remembered that at this time an equal sub-atmospheric pressure is present in both chamber 36 and compartment 37.

The heated oil, purified under partial vacuum by distilling off the objectionable diluents, gradually collects or becomes stored in compartment 37, discharge valve 82 being closed under the assumed condition of the apparatus, because of the atmospheric pressure below it and the sub-atmospheric pressure above it, and when the float therein reaches a predetermined point in its ascent, it causes the quick closing of valves 67 and 68 and the opening of valve 49.

This creates atmospheric pressure in compartment 37, without interrupting or upsetting the sub-atmospheric pressure in chamber 36, resulting in valve 82 dropping to open position due to the weight of the oil above it and to the balanced atmospheric pressures on its two sides.

It should be observed that valve 52 automatically closes under these conditions if it were previously open, due to the greater pneumatic pressure below it, overcoming the head of oil above it, even though the thermostatic bar 53 is flexed to permit its opening, because of the loose or sliding connection between the valve and the bar.

As the oil level in compartment 37 descends during the oil discharge, the float finally reaches a low position where it actuates the spring snap mechanism quickly simultaneously closing valve 49 and opening valve 67, both by hammer blows of the lever or arm 61.

Oil-valves 68 and 52 remain closed, however, owing to their loose connections with the members 61 and 53, respectively, until

reduced or subnormal atmospheric pressure is again established in compartment 37 due to the suction exerted thereon through the now open air-delivery port 32, whereupon both valves open because of balanced pneumatic pressures on their opposite sides, assuming, of course, that the thermostatic bar 53 is downwardly bent to permit such opening of valve 52.

10 All of the parts are now in the positions which they originally occupied and the appliance will function in the manner well understood.

15 Of course, upon the subsequent collection of a substantial body of oil in the compartment 37, the parts of the mechanism will be again operated as described to obtain its delivery back to the motor.

20 Many minor mechanical changes may be incorporated in the appliance presented without departure from the invention as defined by the appended claims and without the sacrifice of any of its material advantages.

25 I claim:

1. In an apparatus for purifying lubricating oil, the combination of an oil-refining chamber having an inlet-port, a discharge-port for gases and vapors, and two oil-delivery ports, means to heat said chamber, a thermostat in said chamber, a valve coacting with one of said oil-delivery ports and governed by said thermostat, a mechanically-operated valve coacting with said other oil-delivery port, and means causing the oil traversing said chamber to be subjected to the action of said heating means when said thermostatically-controlled valve is closed and to be substantially free from such heating action when such valve is open.

2. In an apparatus for purifying lubricating oil, the combination of a structure having an upper oil-refining chamber with an inlet-port, a discharge port for gases and vapors, and two oil-delivery ports connecting said chamber with a lower storage-compartment, the entrances to said two oil-ports in said chamber being at different elevations, means to heat said chamber, a thermostatically-controlled valve coacting with that one of said oil-delivery ports having the lower entrance, and a mechanically-operated valve governing the other oil-delivery port.

3. In an apparatus for purifying lubricating oil, the combination of a structure having an upper oil-refining chamber with an inlet-port, a discharge port for gases and vapors, and two oil-delivery ports connecting with a lower storage-compartment, the entrances for said oil-delivery ports being at different elevations in said chamber, means to heat said chamber, a valve coacting with one of said oil-delivery ports, a thermostat in the lower portion of said chamber

controlling said valve, a valve coacting with the other oil-delivery port, a float in said storage-compartment, means actuated by said float to control said last-mentioned valve at least in part, and means causing the oil traversing said chamber to be subjected to the action of said heating means when said thermostatically-controlled valve is closed and to be substantially free from such heating action when such valve is open. 75

4. In an apparatus for purifying lubricating oil, the combination of a structure having an upper oil-refining chamber with an inlet-port, a discharge-port for gases and vapors, and two oil-delivery ports and an air-port connecting said chamber with a lower storage-compartment, the entrances for said two oil-ports being at different elevations in said chamber, means to heat said chamber, a valve coacting with that one of said oil-delivery ports with the lower entrance, a thermostat in the lower portion of said chamber controlling the action of said valve, a float in said storage-compartment, a valve actuated at least in part by said float controlling said other oil-port, and means causing the oil traversing said chamber to be subjected to the action of said heating means when said thermostatically-controlled valve is closed and to be substantially free from said heating action when such valve is open. 80 85

5. In an apparatus for purifying lubricating oil, the combination of an upper separating-chamber having an inlet port and a discharge port for gases and vapors, a lower storage-compartment having an oil-delivery means therefrom, a division-wall separating said chamber and compartment, a receptacle above said division-wall with its side wall spaced inwardly away from the corresponding wall of said separating-chamber, a heating jacket encasing said separating-chamber, said division-wall having a first oil-port and an air-port therethrough connecting said receptacle and compartment, a second oil-port therethrough connecting said chamber and compartment, a thermostatically-controlled valve governing said second oil-port, said compartment having an air-inlet port, valves to control said air-port, air-inlet port, and first oil-port, a float in said compartment, and connecting means whereby said float actuates said last three-mentioned valves at least in part. 100 105 110 115

6. In an apparatus for purifying lubricating oil, the combination of an upper separating-chamber having an inlet port and a discharge port for gases and vapors, means to heat said separating chamber, a lower storage-compartment having an oil-delivery means therefrom, said apparatus having an oil-port connecting said chamber and compartment, a valve to open and close said oil-port, and thermostatic means having a 120 125 130

loose connection with said valve to operate the latter at least in part, the valve being capable of remaining closed under certain pneumatic pressure conditions, even though the thermostatic means would otherwise permit it to open.

7. In an apparatus for purifying lubricating oil, the combination of an upper separating-chamber having an inlet port and a discharge port for gases and vapors, a lower storage-compartment having an oil-delivery means therefrom, a receptacle in said chamber with its side wall spaced inwardly away from the corresponding wall of said chamber, a heating jacket encasing said separating-chamber, said tank having a first oil-port and an air-port connecting said receptacle and compartment and a second oil-

port connecting said chamber and compartment, a valve to open and close said second oil-port, thermostatic means having a loose connection with said valve to operate the latter at least in part, the valve being capable of remaining closed under certain pneumatic pressure conditions even though the thermostatic means would otherwise permit it to open, said compartment having an air-inlet port, a valve for said first oil-port, a valve for said air-port, a valve for said air-inlet port, a float in said compartment, and connecting means whereby said float actuates said last-three-mentioned valves.

In witness whereof I have hereunto set my hand.

RALPH L. SKINNER.
